[57] ABSTRACT

A bias arrangement makes it possible to automatically compensate the temperature drift occurring in an amplifier transistor. The bias arrangement formed by a first and a second transistor, supplies the bias voltage for an amplifier transistor, which voltage is variable by a variable resistor in the emitter lead of the first transistor. A third transistor identical to the first transistor assembled on the same radiator as the first transistor and the amplifier transistor supplies to the base of the amplifier transistor a voltage proportional to the temperature variations, with a coefficient which is chosen by means of a resistance bridge, in order to precisely compensate the variations of the amplifier transistor.

ARRANGEMENT FOR COMPENSATING THE TEMPERATURE DRIFT OF A POWER AMPLIFIER

The present invention relates to transistor power amplifiers provided with an arrangement for compensating the temperature drift of the power amplifier transistor.

A circuit of this type has been described in French Pat. No. 2,105,557 using regulation transistor which enables the bias voltage of the amplifier transistor to follow a variation which compensates for that produced by the temperature variation. But amplifiers of this type have the drawback that they require an external element, diode or transistor, the temperature drift of which must be the same as that of the power amplifier transistor; in addition they do not comprise any adjusting means.

The present invention makes it possible to overcome this drawbacks.

According to the invention there is provided a power amplifier comprising at least one amplifier transistor having a base, an emitter and a collector, said amplifier transistor for amplifying an input signal being arranged in a common emitter configuration at least as far as the bias is concerned and an arrangement for supplying a bias voltage to the base of said amplifier transistor, said arrangement including: an auxiliary transistor having a base, a collector and an emitter, the emitter of said auxiliary transistor being coupled to the base of said amplifier transistor; a regulating transistor having a base, a collector and an emitter, the collector of said regulating transistor being coupled to the base of said auxiliary transistor; a resistor inserted between the base of said regulating transistor and the emitter of said auxiliary transistor; a further transistor, having the same characteristics as said regulating transistor and having a base, a collector and an emitter, the emitter of said further transistor being coupled to the emitter of said auxiliary transistor; a variable resistor inserted between the base of said regulating transistor and the base of said further transistor, the base and collector of said further transistor being coupled; and means for adjusting the emitter voltage of said regulating transistor; said amplifier transistor, said regulating transistor and said further transistor being assembled on one and the same radiator.

The invention will be better understood and other of its features rendered apparent, from a consideration of the ensuing description given with reference to the appended drawing which represents an embodiment of a transistor amplifier in accordance with the invention.

In this drawing, an NPN transistor Q_3 is a power amplifier transistor connected in a common emitter configuration and the collector of which is connected to a direct supply voltage source V_0 through a high frequency circuit L . The base of the transistor Q_3 is connected to the output of a bias arrangement through a filter circuit F passing the direct current straight through. This output formed the input E of the amplifier, the output S of the amplifier being formed by the collector of Q_3 . The transistor Q_3 is mounted on a radiator RD . The arrangement for biasing the transistor Q_3 comprises the following elements:

A transistor Q_2 connected as a current amplifier, is connected by its collector to the voltage source V_0 through a resistor R_9 and by its emitter to the input E . The base of the transistor Q_2 is connected to ground

through a capacitor C_2 and to the collector of a transistor Q_4 .

The transistor Q_4 and another transistor Q_1 are also assembled on the radiator RD as close as possible to Q_3 .

5 These transistors Q_1 and Q_4 have the same substrate. Their characteristics are therefore identical, by construction. The base and the collector of Q_1 are connected on the one hand to the direct supply voltage source V_0 through a resistor R_2 , and on the other hand to the base of the transistor Q_4 through a variable resistor R_4 .

10 The emitter of the transistor Q_1 is connected to the input E on the one hand and to ground through a resistor R_1 on the other.

15 The collector of the transistor Q_4 is connected to the base of Q_2 as described earlier and to the direct voltage source V_0 through a resistor R_7 . The base of Q_4 is connected to the direct voltage source V_0 through a resistor R_5 , grounded through a capacitor C_1 and connected 20 to the resistor R_3 as described earlier.

25 The emitter of Q_4 is connected to two resistor, one R_8 is connected to the direct voltage source V_0 , while the other R_6 being a variable resistor, is grounded.

The operation of the arrangement at a given fixed 30 temperature, corresponds with that of a stabilised supply: an amplifier circuit compares the output voltage with a reference voltage to ensure that the output voltage is the same.

35 The reference voltage V_R is the emitter voltage of the transistor Q_4 and is fixed by means of the variable resistor R_6 . The bias voltage at the point E is V_E ; V_B is the voltage drop across the terminals of the resistor R_3 , V_{BE} is the voltage drop between base and emitter of Q_4 for a given collector current, V_D being that of Q_1 which is connected as a diode.

This gives the relationship:

$$V_E + V_B - V_{BE} = V_R.$$

40 The resistors have resistances such that at said given temperature $V_B = V_{BE}$.

45 Accordingly $V_R = V_E$; the bias voltage V_E is equal to the reference voltage.

50 The transistors Q_1 and Q_4 are identical; accordingly, the resistors R_2 and R_7 can be so chosen that the voltages V_D and V_{BE} are equal whatever the temperature. The temperature drift of these voltages is of the order of $k = -2 \text{ mV}/\text{C}$.

55 If the temperature of the base-emitter junctions changes because of variations in external conditions, or because of the transfer of a heat quantity through the radiator RD due to Q_3 , then V_D changes to $V_D + \Delta V_D$ and V_{BE} changes to $V_{BE} + \Delta V_{BE}$, $\Delta V_B = \Delta V_{BE} = (k) (\Delta T)$, where ΔT is the temperature variation experienced by these junctions.

60 The voltage V_B therefore changes in association with the variations in V_D , because of the presence of the voltage divider R_3 and R_4 , to:

$$V_B + \Delta V_B = V_R + (\Delta V_B) \frac{R_3}{R_4 + R_3} = V_R + (k) (\Delta T) \frac{R_3}{R_4 + R_3}$$

The bias voltage V_E will therefore vary as a function of the temperature and as a function of the resistance of the variable resistor R_4 , in accordance with the relationship

$$\Delta V_E = (k) \quad 1 - \frac{R_3}{R_4 + R_3} \quad (\Delta T) = (k') (\Delta T)$$

where $k' = (k) \quad 1 - \frac{R_3}{R_4 + R_3}$

Thus, the bias voltage V_E varies linearly as a function of temperature.

The resistances of the resistors R_3 and R_4 as well as the setting of R_4 can be chosen so that k' is equal to the drift factor of the amplifier transistor Q_3 . In this way, a collector current is obtained which is independent of temperature.

In addition, the method of adjusting R_6 and R_4 is very simple: At a given temperature, the adjustment of R_6 makes it possible to set the voltage V_E to the value required to obtain the desired current in the amplifier transistor Q_3 .

Subsequently, the radiator which is common to the three transistors is placed at a different temperature and R_4 is adjusted in order to restore the chosen current in Q_3 . The adjustment thus obtained is valid throughout the operating temperature range.

Moreover, the bias voltage V_E is relatively independent of the circuit supply voltage V_0 since the current in R_2 and R_3 varies proportionally with the reference voltage V_R which is obtained by division of V_0 .

The output impedance of the device is very low and substantially equal to: $(1/\beta Gm)$ where β is the current gain of the transistor Q_2 and Gm the slope of the voltage-current characteristic of Q_4 .

The invention is not limited to the embodiment described and illustrated.

In particular, the transistor Q_2 can be connected to one or several supplementary transistors with the object of achieving a higher current gain. In addition, the amplifier may comprise supplementary capacitors designed to prevent oscillation and to eliminate the high frequency coming from the circuits of Q_3 .

40

45

On the other hand, the transistor Q_2 has been shown outside the radiator R_D although it could, without any drawback, be assembled on the radiator.

Finally, the power amplifier may comprise several power amplifier transistors having identical characteristics, in particular for symmetrical class B power amplifier circuits, receiving the same bias voltage.

Of course, the invention is not limited to the embodiments described and shown which were given solely by way of example.

What is claimed is:

1. A power amplifier comprising at least one amplifier transistor having a base, an emitter and a collector, said amplifier transistor for amplifying an input signal being arranged in a common emitter configuration at least as far as the bias is concerned and an arrangement for supplying a bias voltage to the base of said amplifier transistor, said arrangement including: an auxiliary transistor having a base, a collector and an emitter, the emitter of said auxiliary transistor being coupled to the base of said amplifier transistor; a regulating transistor having a base, a collector and an emitter, the collector of said regulating transistor being coupled to the base of said auxiliary transistor; a resistor inserted between the base of said regulating transistor and the emitter of said auxiliary transistor; a further transistor, having the same characteristics as said regulating transistor and having a base, a collector and an emitter, the emitter of said further transistor being coupled to the emitter of said auxiliary transistor; a variable resistor inserted between the base of said regulating transistor and the base of said further transistor, the base and collector of said further transistor being coupled; and means for adjusting the emitter voltage of said regulating transistor; said amplifier transistor, said regulating transistor and said further transistor being assembled on one and the same radiator.

2. A power amplifier as claimed in claim 1 wherein said regulating transistor and said further transistor have a common substrate.

3. A power amplifier as claimed in claim 2 wherein said auxiliary transistor is assembled on said radiator.
